UNITED STATES PATENT OFFICE.

ARCHIE C. CURRIE, OF SPRINGFIELD, OHIO, ASSIGNOR TO THE SPRINGFIELD METAL-LIC CASKET COMPANY, OF SPRINGFIELD, OHIO, A CORPORATION OF OHIO.

DESIGN FOR A BURIAL CASKET.

Application filed December 22, 1924. Serial No. 11,764. Term of patent 14 years.

To all whom it may concern:

Be it known that I, ARCHIE C. CURRIE, a citizen of the United States, residing at Springfield, in the county of Clark and State of Ohio, have invented a new, original, and ornamental Design for Burial Caskets, of which the following is a specification, reference being had to the accompanying drawing, forming part thereof.

Fig. 1 is a side elevation of a burial casket showing my design.

Fig. 2 is an enlarged end elevation of the same.

I claim:

The ornamental design for a burial casket, as shown.

ARCHIE C. CURRIE.
